UNITED STATES PATENT OFFICE.

HARRY LANDSIEDEL, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

RECORDING-MACHINE.

1,123,323.

Specification of Letters Patent.

Patented Jan. 5, 1915.

Application filed September 29, 1913. Serial No. 792,408.

To all whom it may concern:

Be it known that I, HARRY LANDSIEDEL, a citizen of the United States, residing at Poplar Bluff, Missouri, have invented a new and useful Recording-Machine, of which the following is a specification.

This invention relates to recording machines of the type which employ a revoluble platen, and paper feed mechanism arranged to coöperate with the platen to feed the paper in line spacing, and it consists of novel devices for actuating the paper feed mechanism, all of which are illustrated in the accompanying drawings, and are hereinafter described and claimed.

An object of the invention is to provide an improved paper feed mechanism which is operable and adjustable to feed the paper varying distances, and means for adjusting and retaining the actuating devices for the feed mechanism in their different adjustments, in combination with a lever which is operable to disable the actuating devices in any of the adjustments thereof, whereby the platen will be prevented from moving in line spacing operations.

Other objects will appear from the following description, reference being made to the accompanying drawings in which I have illustrated one embodiment of my invention, and in which—

Figure 1 is a side elevation of a "Dalton" adding machine having my invention embodied therein. Fig. 2 is an end elevation 35 of the paper carriage with the platen knob removed, illustrating the actuating devices of the paper feed mechanism in operative adjustment for actuating the feed mechanism to move the paper three spaces. Fig. 3 is a 40 similar view illustrating the actuating devices disabled by the non-space lever. Fig. 4 is a front elevation of a portion of the platen and paper carriage having my invention combined therewith. Fig. 5 illustrates 45 the line spacing devices adjusted for feeding the paper a single space, the parts being shown in retracted position so that forward movement of the actuating pawl will rotate the platen and feed the paper. Fig. 6 is a 50 similar view showing the actuating pawl advanced after having actuated the platen. Fig. 7 is a detail sectional view illustrating the adjustable support for holding the actu-

ating pawl in different adjustments whereby it will actuate the platen as required to feed the paper varying distances.

It is obvious that the present invention may be used upon any of the recording machines containing a revoluble platen which is operable in connection with the feed rolls to move the paper in line spacing. For convenience of illustration I have illustrated my invention combined with an adding machine, but I do not restrict myself to use in connection with adding machines, and I desire it to be understood that I claim my invention in any embodiment in which it is capable of use.

The platen 1 is supported upon a shaft 2 which is revolubly journaled in bearings in a carriage 3. The carriage 3 is laterally movable upon a suitable support 4. A number of independently acting pressure rolls 5^a (Fig. 4) are mounted in the carriage and are arranged to coöperate with the platen to actuate the paper in its line spacing movement. Actuation of the paper is effected by direct rotation of the platen through the engagement of the actuating devices with a ratchet wheel 5 which is attached to the shaft 2.

A rock shaft 6 is supported in bearings in the carriage 3 and an arm 7 is attached to one of the ends of said rock shaft. The arm 7 has a pin 8 which extends through a slot 9, (Fig. 6), in one of the side members of the carriage 3, and thereby limits the rocking movement of the shaft 6. A spring 10 has its rear end connected to the pin 8 and its front end connected to a pin 11 on the side member of the carriage, so that said spring actuates the arm 7 forwardly. The arm 7 is provided with three holes 12 which are connected by slots 13 somewhat narrower than the width of the holes, so that an element fitting within one of the holes is unable to move laterally through the slots 13, although an element capable of moving through the slots 13 may be moved from one to another of the holes 12 without withdrawing such element from said holes. A small bolt 14 extends through the passage formed by the holes 12 and the slots 13 and pivotally supports an actuating pawl 15 upon its inner end. The actuating pawl 15 is arranged to engage with the ratchet wheel 5 and actuate

said ratchet wheel and thereby operate the platen and the feed rolls to effect movement of the paper in line spacing. A sleeve 16 is mounted on the outer part of the bolt 14 and is provided in its outer end with a recess 17 capable of receiving the head of the bolt, and constituting a seat for a spring 18 (Fig. 7), which encircles the bolt and presses against the head thereof. The sleeve 16 is provided with a reduced inner end 19 capable of moving into any one of the three holes 12, but incapable of passing through the slots 13. Thus, when the reduced portion 19 of the sleeve 16 is seated in any one of the holes 12 it will be retained in such position because of the inability of said sleeve to pass through the slots 13. The inner end of the sleeve will be retained in any one of the holes 12 in which it may be seated by the power of the spring 17. The outer part of the sleeve 16 is provided with a manually engageable portion 20, so that said sleeve may be manually withdrawn from any one of the holes 12 in which it may be seated, to enable the bolt 14 to be moved from one to another of said holes. Thus, the actuating pawl 15 may be adjusted in different positions with respect to the rock shaft 6, so that said actuating pawl will be moved varying distances as required to move the paper one or two or three spaces, as desired. When the actuating pawl is supported at the lowest hole 12 it may be operated to move the paper a single space; when supported at the intermediate hole 12 it may be operated to move the paper two spaces; and when supported at the outer hole 12 the actuating pawl may be operated to move the paper three spaces; and said pawl may be adjusted and retained in either one of said positions as above explained.

The free end of the pawl is actuated toward the ratchet wheel 5 by a spring 21 connecting said pawl with the side of the carriage. The front end of the pawl 15 is provided with a lateral extension 22 (Fig. 4), which, as the pawl approaches the end of its forward movement, engages a roller 23 and is thereby disengaged from the ratchet wheel 5. The roller 23 is supported upon a stud extending from the side member of the carriage 3, and is in position to disengage the pawl 15 from the ratchet wheel 5 at the same point in the forward movement of the pawl, irrespective of whether the pawl is supported at one or the other of the holes 12.

The shaft 6 may be rocked by any suitable means. In the embodiment shown a lever 24 is slidably keyed on the shaft and is capable of operation to rock said shaft and thereby move the actuating pawl 15 to actuate the line spacing devices.

In the normal or idle position of the parts the projection 22 on the pawl 15 rests against the roller 23, and is thereby retained out of

engagement with the ratchet wheel, as shown in Fig. 6. Thus, the actuating pawl is normally disengaged from the ratchet wheel, so that the platen may be otherwise rotated independently of said actuating pawl and while said pawl is disengaged therewith. The platen is provided with a knob 25 for effecting such independent rotation. The spring 10, which actuates the arm 7 forwardly as previously explained, yieldingly holds the actuating devices in their idle position in which the pawl 15 is upon the roller 23 and out of engagement with the ratchet wheel 5.

The "Dalton" adding machine in which I have illustrated my invention is provided with a rock shaft 26 capable of being rocked by manipulation of the lever 27. Said shaft is provided with an arm 28 which is connected with a link 29. The upper end of the link 29 is pivoted to the rearwardly extending arm of the bell-crank lever 30 mounted on a support 31. The upper arm of the lever 30 is provided with a slot 32 which receives a roller 33 which is supported by the lever 24. When the carriage 3 moves laterally the lever 24 is prevented from moving laterally by a bracket 24^a attached to the support 4 and projecting on opposite sides of said lever 24. When the lever 27 is drawn forwardly the connections therefrom will actuate the rod 33 and lower end of the lever 24 forwardly, thereby rocking the shaft 6 and moving the actuating pawl 15 rearwardly from the position shown in Figs. 1 and 6, to the positions shown in Figs. 2 and 5. Return movement of the lever 27 rocks the shaft 6 in the opposite direction, movement of said shaft 6 being assisted by the spring 10, thereby engaging the pawl 15 with the ratchet wheel 5 and actuating said ratchet wheel until said pawl is disengaged therefrom by the roller 23. The extent of movement of the pawl and of the ratchet wheel 5 will be determined by the position in which the actuating pawl is supported; that is to say, whether said pawl is supported at one or the other of the holes 12.

On some occasions it is desirable to permit operation of the shaft 26 without moving the paper in line spacing. This is particularly true in certain operations of adding machines, with which I have illustrated my invention. A lever 34 is pivotally supported at 35 by one of the side members of the carriage. The lower end of the lever 34 curves under the platen shaft, as clearly shown in Fig. 3, and is provided with a rounded camming part 36 at its end. The cam part 36 operates against a stud 37 on the side of the carriage. The camming-like end 36 of the lever 34 cooperates with the stud 37 to hold the lever 34 in either of its two adjustments. In one of said adjustments the part 36 is above the axis of the

stud 37, and thereby holds the lever 34 above the ratchet teeth on the wheel 5 so that the pawl 15 may engage with said wheel. Movement of the lever 34 to the position shown in Fig. 3 carries the cam-like part 36 below the axis of the stud 37, thereby holding the arcuate under edge of the lever 34 below the teeth of the wheel 5, so that the projection 22 on the pawl 15 rubs against the under edge of said lever 34 and is thereby prevented from engaging the ratchet wheel. Thus, the pawl 15 may be moved without actuating the platen, as a result of which adjustment the shaft 26 is enabled to operate without feeding the paper. An extension 39 on the upper end of the lever 34 constitutes a handle for manual engagement for operating said lever. It will be understood that the lever yields to permit movement as required to engage the portion 36 above or below the stud 37 as above explained. Movement of the lever 34 is limited by a pin 40 on the side of the carriage extending into a slot 41 in the lever.

The platen detent includes an arm or lever 42 pivoted upon a support 43 and having a small roller 44 operating upon the periphery of the wheel 5 so as to hold the platen in its different line space adjustments. A pin 45 on the arm 42 extends through a slot in the side of the carriage 3. A spring 46 connects the pin 45 with a projection on the carriage and thereby yieldingly holds the roller 44 upon the ratchet wheel, but permits rotation of the ratchet wheel when the pawl 15 is actuated.

I have illustrated my invention mounted in a "Dalton" adding machine, with provision for operating the lever 24 from one of the shafts of the adding machine. It is to be understood, however, that I do not restrict myself to an embodiment in which the lever 24 is mechanically operated, for it is obvious that said lever may be manually operated, which may be the preferred method of operation when the invention is used upon a typewriter. It is apparent also that there may be other variations in the construction and arrangement of the parts to conform to the requirements of different machines, and that such variations are within the mechanical skill of those skilled in the art, and are clearly embraced within the scope of the present invention.

What I claim and desire to secure by Letters Patent of the United States is:

1. In a recording machine, the combination with a platen, and a ratchet wheel for rotating said platen, of a rock shaft, an arm supported by said rock shaft, a pawl supported on said arm adapted to engage with and actuate said ratchet wheel, a spring actuating said pawl into engagement with said ratchet wheel, means for rocking said shaft and thereby actuating

said pawl, and an element engaged by said pawl while said pawl is rotating said ratchet wheel, effectively to disengage said pawl from said ratchet wheel during continued movement of said pawl. 70

2. In a recording machine, the combination with a platen, and a ratchet wheel for rotating said platen, of a rock shaft, an arm supported by said rock shaft, a pawl supported on said arm adapted to engage with 75 with an actuate said ratchet wheel, means for rocking said shaft and thereby actuating said pawl, means for holding said pawl in different positions to vary extent of movement thereof, and an element engaged 80 by said pawl while said pawl is rotating said ratchet wheel, effectively to disengage said pawl from said ratchet wheel during continued movement of said pawl, in the same direction in which it was moving while 85 rotating said ratchet wheel.

3. In a recording machine, the combination with a platen, of a rock shaft, an arm supported by said rock shaft, a pawl supported by said arm adapted to engage with 90 and rotate said ratchet wheel when moved in one direction by said arm, and a mechanical element for disengaging said pawl from said ratchet wheel while said pawl is moving in the same direction in which it moves 95 when rotating said wheel.

4. In a recording machine, the combination with a platen, and a ratchet wheel for rotating said platen, of a rock shaft, an arm supported by said rock shaft, a pawl supported by said arm and arranged to engage with and rotate said ratchet wheel, 100 means for holding said pawl in different adjustments on said arm for varying the movement of said pawl and said ratchet 105 wheel and said platen, a lever for rocking said shaft, and means for operating said lever.

5. In a recording machine, the combination with a platen, and a ratchet wheel for 110 rotating said platen, of a pawl arranged to engage with and rotate said ratchet wheel, a spring for actuating said pawl into engagement with said ratchet wheel, means for moving said pawl in a direction to rotate 115 said wheel, means for supporting said pawl in different positions to vary extent of movement thereof, and means for disengaging said pawl from said wheel while said pawl is moving in the same direction 120 in which it moves to rotate said wheel.

6. In a recording machine, the combination with a platen, and a ratchet wheel for rotating said platen, of a rock shaft, an arm attached to said rock shaft, a pawl, a 125 support for holding said pawl in different positions upon said arm and movable bodily to different positions upon said arm to vary the extent of movement of said pawl when said shaft and arm are operated, and 130

- means for operating said shaft and said arm and thereby said pawl effectively to rotate said ratchet wheel and said platen.
7. In a recording machine, the combination with a platen, and a ratchet wheel for rotating said platen, of a rock shaft, an arm attached to said rock shaft, a pawl, a support for said pawl movable bodily to different adjustments upon said arm to vary extent of movement of said pawl, a lever for rocking said shaft to move said pawl in one direction, and separate means for actuating said pawl in the opposite direction.
8. In a recording machine, the combination with a platen, and a ratchet wheel for rotating said platen, of a rock shaft, an arm attached to said rock shaft, a pawl supported by said arm, a lever for rocking said shaft to move said pawl in one direction, a spring for actuating said pawl in the opposite direction effectively to engage with and rotate said ratchet wheel, and means for disengaging said pawl from said ratchet wheel in each last named movement of said pawl.
9. In a recording machine, the combination with a platen, and a ratchet wheel for rotating said platen, of a pawl for rotating said ratchet wheel, means for supporting said pawl in different positions to vary extent of movement thereof, manual means for operating said pawl in one direction, and automatic means for actuating said pawl in the opposite direction effectively to rotate said ratchet wheel and platen.
10. In a recording machine, the combination with a platen, and a ratchet wheel for rotating said platen, of a pawl for actuating said ratchet wheel, means for operating said pawl in one direction, means for actuating said pawl in the opposite direction effectively to rotate said ratchet wheel and said platen, and means for disengaging said pawl from said ratchet wheel while said pawl is moving in said last-named direction.
11. In a recording machine, the combination with a platen, and a ratchet wheel for rotating said platen, of a pawl for actuating said ratchet wheel, manual means for moving said pawl in one direction, automatic means for moving said pawl in the opposite direction and thereby rotating said ratchet wheel and said platen, and means for supporting said pawl in different positions to vary the extent of movement of said pawl.
12. In a recording machine, the combination with a platen, and a ratchet for rotating said platen, of a pawl, means for actuating said pawl effectively to rotate said ratchet wheel and platen, a device for disengaging said pawl from said ratchet wheel during movement of said pawl, and an element for preventing said pawl from engaging said ratchet wheel and said device.
13. In a recording machine, the combination with a platen, and a ratchet wheel for rotating said platen, of a pawl, means for actuating said pawl effectively to rotate said ratchet wheel and platen, a curved lever pivoted adjacent to said ratchet wheel, a stud adjacent to said lever, and a projection on said lever engaging said stud effectively to hold said lever in position to prevent said pawl from engaging said ratchet wheel or in position to permit said pawl to engage said ratchet wheel as desired.
14. In a recording machine, the combination with a platen, and a ratchet wheel for rotating said platen, of a pawl for actuating said ratchet wheel, means for operating said pawl, an abutment for preventing said pawl from engaging said ratchet wheel, a stud for holding said abutment in position to prevent said pawl from engaging said ratchet wheel or to permit said pawl to engage said ratchet wheel as desired, and a manually engageable extension on said abutment for operating said abutment.
15. In a recording machine, the combination with a platen, and a ratchet wheel for rotating said platen, of a pawl for actuating said ratchet wheel, means for operating said pawl, an arcuate resilient element adjacent to said ratchet wheel and provided with a slot, a stud extending into said slot and limiting movement of said element, means for positioning said element in a plane below the teeth of said ratchet wheel so that said pawl will rub against said element and be prevented from engaging said ratchet wheel, a cam-part on said element, and a stud engaged by said cam-part for holding said element so positioned.
16. In a recording machine, the combination with a platen, and a ratchet wheel for rotating said platen, of a pawl for actuating said ratchet wheel, means for operating said pawl, an arcuate element adjacent to said ratchet wheel, means for moving said arcuate element to a position in which the outer edge thereof is in a plane outside the plane of the periphery of said ratchet wheel, means for holding said element in such position, a device independent of said last-named means limiting movement of said element, and a part on said pawl engaging said element in the position aforesaid and holding said pawl out of engagement with said ratchet wheel during operation of said pawl.
17. In a recording machine, the combination with a platen, and a ratchet wheel for rotating said platen, of a pawl for actuating said ratchet wheel, means for operating said pawl, an element supported adjacent

to said ratchet wheel, means for moving said element to a position in which its outer edge is in a plane outside the plane of the periphery of said ratchet wheel, a cam and 5 stud device holding said element in the position aforesaid, a projection on said pawl engaging said element when said element is positioned as aforesaid effectively to prevent said pawl from engaging said ratchet

wheel, and means for actuating said pawl into engagement with said element.

In witness whereof I have signed this specification in the presence of two subscribing witnesses.

HARRY LANDSIEDEL.

Witnesses:

HARRY C. YAEGER,
BIRNEY DYSART.

Correction in Letters Patent No. 1,123,323.

It is hereby certified that in Letters Patent No. 1,123,323, granted January 5, 1915, upon the application of Harry Landsiedel, of Poplar Bluff, Missouri, for an improvement in "Recording-Machines," an error appears in the printed specification requiring correction as follows: Page 3, line 76, for the word "an" read *and*; and that the said Letters Patent should be read with this correction therein that the same may conform to the record of the case in the Patent Office.

Signed and sealed this 2nd day of February, A. D., 1915.

R. F. WHITEHEAD,

Acting Commissioner of Patents.

[SEAL.]
